Edward Gwynn.

UNITED STATES PATENT OFFICE.

STUART GWYNN, OF NEW YORK, N. Y., ASSIGNOR TO THE AMERICAN METALINE COMPANY, OF SAME PLACE.

IMPROVEMENT IN JOURNAL-BOX LININGS.

Specification forming part of Letters Patent No. **138,642**, dated May 6, 1873; application filed February 3, 1873.

To all whom it may concern.

Be it known that I, STUART GWYNN, of the city, county, and State of New York, have invented a new manufacture, the same being an Improved Lining for Journal-Boxes and other rubbing surfaces, of which the following is a specification, reference being had to the accompanying drawing forming part of the same.

On the 12th day of April, 1870, certain Letters Patent of the United States were issued to me numbered from 101,862 to 101,869, inclusive, for certain compositions of matter denominated "Metaline," and for the process or method of making the same, as also the offices it performs, to which reference is made. The invention herein intended to be described and claimed relates to a special mode of applying the said several kinds of metaline, or any of them, or their equivalent, to practical use; and consists in a combination of metaline with the material, in the manner and for the purposes hereinafter particularly described.

Figure 1 is an edge view of a corrugated sheet of metal, the corrugations being filled with metaline—the first step in the process of making my new manufacture. Fig. 2 is a perspective surface view of the same. Fig. 3 is an edge view of the same after being subjected to pressure. Fig. 4 is a perspective surface view of the latter.

In fabricating the article intended here to be described, I take a sheet of suitable metal, preferably of copper or brass, and corrugate

it, filling the corrugations with any one of the varieties of metaline described in my patents of April 12, 1870, hereinbefore referred to, or their equivalent, the corrugations being preferably formed so that the metal on one side is turned down at right angles to the surface of the sheet, while the other is inclined to form the corrugation, whereby the corrugations, when the sheet is subjected to pressure, will all fold down upon the sheet and all in one direction. The sheet thus prepared is then subjected to great pressure, either between plane surfaces or suitable corrugated rolls, or both, by which the corrugations are folded down upon the sheet, and the metaline that is held in the folds compressed and consolidated, a portion of the metaline being exposed on the surface of the completed sheet at the top of each of the folds, thereby presenting a rubbing surface of metaline.

Journal-box lining thus formed may be cut into strips and laid in recesses made in the face of the box, or the entire face may be lined with it. It can, of course, be applied to plane rubbing surfaces as well as for the bearings of revolving shafts.

What I claim, as a new manufacture, is—
A sheet of corrugated metal with which is incorporated metaline, substantially as and for the purposes specified.

STUART GWYNN.
